(57) **CLAIM**

The ornamental design for a fork, as shown.

DESCRIPTION

FIG. 1 is a front elevation view of the fork;

FIG. 2 is a back elevation view of the fork of FIG. 1;

FIG. 3 is a left side elevation view of the fork of FIG. 1;

FIG. 4 is a right side elevation view of the fork of FIG. 1;

FIG. 5 is a top plan view of the fork of FIG. 1;

FIG. 6 is a bottom plan view of the fork of FIG. 1;

FIG. 7 is a perspective view of the fork of FIG. 1;

FIG. 8 is an enlarged partial view taken along line 8—8 of the fork in FIG. 1;

FIG. 9 is an enlarged cross-sectional end view taken along line 9—9 of the fork in FIG. 8; and,

FIG. 10 is an enlarged partial perspective view of a fork tine in FIG. 1.

The broken lines in FIG. 7 is for illustrative purposes only and forms no part of the claimed design.
